FAUCET

Arthur L. Boscow and Arnold V. Worthington,
Oakland, Calif.

Application May 7, 1936, Serial No. 78,390

2 Claims. (Cl. 251—4)

The invention relates to faucets and more particularly to domestic water faucets such as the common sink or basin faucet.

An object of the invention is to provide a faucet of the character described which, in addition to its usual use as a basin or sink faucet, may be quickly and easily converted into a drinking fountain and will automatically control fluid flow therethrough when changed from one form to the other to afford a full discharge of fluid when used as a faucet, and a restricted and proper height of liquid discharge when used as a fountain.

Another object of the invention is to provide a faucet of the character above described which may be readily adjusted to produce a proper height of liquid discharge for drinking when installed in a water or other fluid systems of different pressures.

A further object of the invention is to provide a faucet of the character described, which will be simple and inexpensive in manufacture and which may be embodied in the existing types of faucets without requiring a substantial change in their construction.

The invention possesses other objects and features of advantage, some of which, with the foregoing will be set forth in the following description of the preferred form of the invention. It is to be understood, however, that variations in the mode of effecting the invention as explained in the description may be adapted within the scope of the invention as set forth in the claims.

Referring to said drawing:

Figure 1 is a plan view of a faucet constructed in accordance with the present invention.

Figure 2 is a sectional view of the faucet taken substantially on the plane of line 2—2 indicated in Figure 1 and showing the faucet arranged in conventional form.

Figure 3 is a sectional view similar to Figure 2 but showing the faucet arranged as a drinking fountain.

The faucet illustrated in the accompanying drawing is of the common sink or basin type comprising, a pair of spaced valve casings 6 and 7 which are provided with inlet passages 8 and 9 arranged for connection to the hot and cold water mains 11 and 12 and have a common interconnecting mixing conduit chamber 13 to which is connected, by means of a swivel head 14, a discharge conduit 16. In accordance with the more or less standard design of this general type, the faucet casings 6 and 7 are provided with the

manually controlled valves 17 and 18 which are interpositioned between the inlet passages 8 and 9 and the mixing chamber 13 for regulating the amount of hot and cold water admitted to the chamber 13 for discharge through the conduit 16. 5

Preferably the conduit 16, as by means of the swivel head 14, is pivotally connected to the conduit 13 for movement about a vertical axis to permit the positioning of the conduit 16 at various horizontal positions over the sink or basin 10 in connection with which it is used. As here shown, this pivotal connection is provided by threading a reduced lower end 19 of the head 14 into a raised offset portion 21 provided on an intermediate portion of the conduit 13 and providing these engaged portions with registration passages 22 and 23, which are communicated by way of the passage 23 with the main passage 24 provided in the conduit 13. Preferably a packing gland 26 is secured to the portions 19 and 21 20 for preventing leakage.

As an important feature of the faucet the outer or discharge end 25 of the conduit 16 is angularly related to the length of the conduit and, in accordance with the present invention, 25 the conduit is pivotally associated with the head 14 for rotation about a generally horizontal axis whereby the discharge end 25 of the conduit may be disposed in a downwardly opening position for use as a conventional faucet, or may be positioned in an upwardly opening direction to convert the faucet into a drinking fountain. As will be understood, this conversion feature made possible by the combination of the angularly related discharge end of the conduit and the swivel 30 35 or pivotal connection of the conduit with the head 14 entails substantially no change in the conventional faucet construction, except for the embodiment of these features in the discharge conduit and the swivel head 14 of the faucet. 40

The pivotal connection between the conduit 16 and the swivel head 14 is illustrated in the accompanying drawing in Figures 2 and 3, where, as shown the head 14 is provided with a horizontally extending opening or cylinder 27 which 45 is communicated at a side with the passage 22 and which rotatably receives an end 28 of the conduit 16, the latter being held in the opening against longitudinal withdrawal by means of a packing gland 29 secured to the head 14 and 50 mounted about the conduit 16 at the outer side of an annular shoulder 31 which is preferably contained within a recess 32, formed in the outer face 33 of the head.

As another important feature of the present 55

invention there is incorporated within the faucet an automatically controlled liquid flow means which will afford, in the downward position of the end 25 of the discharge conduit, a full and unimpeded flow of fluid from the faucet, but will effect a reduction in the fluid flow when the conduit 16 is turned to provide a drinking fountain so that the height of the fountain will be confined to a desired amount to permit convenient 10 drinking therefrom by the user. In the present design this automatic flow control means is provided directly in the connection between the conduit 16 and the swivel head 14. As will be seen from Figures 2 and 3, the inner end 28 of the 15 conduit is extended directly across the passage 22 in the head and the inner extremity 34 of the conduit end is closed whereby the only fluid flow from passage 22 into the conduit 16 is afforded through a pair of circumferentially 20 spaced openings 36 and 37 through the wall of the end 28 and in the plane of the passage 22. In accordance with the present arrangement these openings are provided at diametrically 25 spaced positions on the circumference of the conduit so that on rotation of the conduit 16 these openings may be advanced into registration with the passage 22 to communicate the discharge conduit 16 with this latter passage when the end 25 is in its upward and downward position, the 30 opening 37 being registered with the passage 22 when the discharge end of the conduit is turned to the downward opening position, and the opening 36 being placed in registration with the passage 22 when the discharge end 25 of the conduit is rotated to an upward opening position. Thus, openings 36 and 37 control the amount of 35 liquid which is discharged from the conduit in its fountain and faucet positions respectively, and since a substantially less flow is desired for a 40 drinking fountain the opening 36 is considerably smaller than the opening 37. Generally, since little or no reduction of pressure is desired when the conduit is in usual faucet position, the opening 37 desirably approximates the size of the 45 passage 22 whereby no substantial constriction will be produced. On the other hand, since but a relatively low column of liquid is desired with the conduit in a drinking fountain position the opening 36 will need be relatively smaller for the 50 ordinary range of pressures present in various water supply systems. In order, however, that the height of the fountain may be accurately adjusted for different liquid pressures we preferably provide means for changing the effective 55 size of the opening 36. In the embodiment of the invention here illustrated this is provided by adjusting the longitudinal position of the conduit in the opening 27 and thereby adjusting the amount of the opening 36 exposed to the passage 22 by the installation or removal of one or more of a plurality of shims or washers 38 at the inner side of the annular shoulder 31. While this adjustment is a very slight one, it will have an appreciable effect on the opening 36 due to 60 its relative smallness, but will ordinarily have

no appreciable action on the opening 37 due to its relatively greater size.

The positioning of the openings 36 and 37 at diametrically spaced positions on the circumference of the conduit end 28 leaves the intermediate portion of the circumference entirely imperforate and as the conduit 16 is rotated to an intermediate position, that is, with the end 25 more or less horizontally disposed and with the openings 36 and 37 removed from the passage 22, there will be complete stoppage of the fluid flow through the conduit. This is of particular importance in the type of faucet here illustrated embodying both a hot and cold water valve, since once a desired mixture of hot and cold water 15 has been adjusted the fluid flow may be stopped or established by merely rotating the conduit 16 without interfering with the hot and cold water control valves 17 and 18 or disturbing the relative proportion of the hot and cold water delivery 20 therefrom. Also in turning the conduit from faucet to drinking fountain position the large flow of water present in the first position will be automatically stopped entirely and then re-established at a reduced flow for proper drinking fountain height without requiring any change 25 in the setting of the valves 17 and 18.

We claim:

1. A faucet having inlet and discharge passages and a valve for regulating the fluid flow through 30 said passages and an open ended cylinder communicated at a side thereof with said discharge passage, a conduit having a closed end rotatably mounted in said cylinder and a discharge end angularly related to the length of said conduit 35 and positionable on rotation of said conduit in an upwardly and a downwardly opening position, said first named conduit end being provided with a pair of substantially diametrically opposed openings registerable with said discharge 40 passage in the downward and upward positions of said other conduit end, the opening in registration with said passage in the upward position of said end being reduced in size from the other opening, means sealing said first conduit end in 45 said cylinder, and means for adjusting the conduit lengthwise in said cylinder for varying the amount of said last named openings placed in registration with said discharge passage.

2. A faucet comprising a body member provided with a horizontally extending cylindrical bore and a fluid passageway leading into said bore at a side thereof, a discharge conduit having a cylindrical portion fitting in said bore for rotation about the axis of the bore and provided with diametrically opposed openings alternately registering with said passageway upon rotation of said conduit, and means adjustably positioning said conduit longitudinally in said bore for varying the registration of said openings with said 60 passageway independent of the rotative positioning of the conduit.
